UNITED STATES PATENT OFFICE.

FRANK M. ASHLEY, OF NEW YORK, N. Y.

DRILL-CHUCK.

No. 896,052.

Specification of Letters Patent.

Patented Aug. 11, 1908.

Original application filed January 6, 1906, Serial No. 294,877. Divided and this application filed December 8, 1906.
Serial No. 346,986.

To all whom it may concern:

Be it known that I, FRANK M. ASHLEY, a citizen of the United States of America, and residing at West Sixth street, near Neptune 5 avenue, in the city of New York, borough of Brooklyn, State of New York, have invented certain new and useful Improvements in Drill - Chucks, of which the following is a specification:

10 My invention relates to drill chucks and particularly to that type in which the jaw members move at an incline to the axis of the chuck; the subject matter of the present case constituting a division of my application 15 for patent filed January 6, 1906, Serial No. 294,877.

The object of my invention is to provide a chuck in which the body portion may be so constructed as to avoid the weakness caused 20 by cutting an annular groove therein, and to avoid the necessity of making a two part sleeve or ring to operate the jaws.

A further object is to provide extreme strength at the front end of the chuck to resist the lateral thrust of the jaws, while at the 25 same time, a one piece sleeve meshes directly with exposed threaded portions of the jaws and besides having a bearing on the front end of the chuck, reinforces the latter to contribute to the extreme strength previously 30 alluded to.

My invention consists in the novel features and combinations of parts set forth in the subsequent detailed description.

35 Referring to the drawings which form part of this specification, Figure 1, is a drawing, partly in section, which shows the sleeve provided with a rack at its forward end adapted to engage with a pinion wrench. Fig. 2, 40 illustrates the pinion wrench. Fig. 3, is an exterior view of the body portion of the chuck, the guide ways therein being partly indicated by dotted lines.

A indicates the chuck body which is of integral character and is smallest in diameter 45 at its front end and is made cone shaped at its rear end as shown in Fig. 3.

The body is provided with three cylindrical guide ways G, spaced equally from each 50 other and at an incline to the axis of the chuck, and located, one in each of these guide

ways, is a jaw shank E provided with a jaw E' at its front end.

The jaw-shanks are each provided with a thread E² which engages with a thread 55 B' formed on the integral inner wall of the sleeve B.

The sleeve B closely conforms to the body portion, and the threaded part of the jaw-shank E projects above the radius of the 60 body so that the thread B' will enter into mesh with the thread E² and when the sleeve B is rotated, the shanks move in the guide-ways to open or close the jaws in a manner well known in the art.

65 The ring C is screwed on the sleeve B at C' and forms a sliding joint with the body A at A', thereby covering the guide-way openings G at their rear ends, thus keeping out dirt, and also serves as an abutment to prevent the 70 sleeve B from becoming disengaged from the body A.

A rack D is formed on the front end of the sleeve B, and a hole A² is drilled in the chuck-body so that the end H' of the wrench H 75 shown in Fig. 2, may project therein whereby the pinion H² will mesh with the rack D, and by turning the wrench on its axis from left to right, the sleeve B will act to close the jaws of the chuck.

80 It is important that the rack should be located at the front end of the chuck as shown in order to have the chuck work right handed as it is termed by mechanics, since this is the natural and customary way to 85 turn the sleeve in order to close the jaws of the chuck.

The chuck-body is provided with a tapered opening at its rear end in the usual manner for the reception of the arbor F, by which it 90 is driven.

The sleeve drives the shanks directly and the retaining ring C serves the double function of closing the guide-way openings and as an abutment to prevent the sleeve from 95 becoming displaced.

The hole A² is located in the body proper so that the sleeve can be turned in the natural and usual direction of turning a wrench, to effect the closing of the jaws, and the 100 chuck may be easily assembled or taken apart without special tools.

It will be noted that the guide-ways G indicated by dotted lines in Fig. 3, pass through the solid portion of the chuck-body at its front end and the side of the rear portion of the chuck body so that the jaws are firmly supported against lateral movement at this point and lateral thrust incurred by the jaws, resisted, which I consider of great importance.

10 The guide-ways are cylindrical in form and the shanks are fitted to work in sliding engagement.

The front end of the body portion projects beyond the end of the sleeve and thus serves 15 to support the end of the wrench while the sleeve is being rotated.

It will be noted that in addition to providing the sleeve B, with a rotative support at its rear end, the forward portion of said 20 sleeve rotatively bears on the forward portion of the body, thereby supporting the sleeve at such point while at the same time, said sleeve reinforces said forward body portion against lateral thrust incurred by the 25 jaw members, this being particularly important in view of the fact that the obliquity of the guideways results in the metal of the forward body portion immediately above said ways, rearwardly tapering to an edge, 30 and hence the sleeve reinforces said tapering metal at the points where it is weakest.

The sleeve being threaded directly on its inner surface allows of a considerable length 35 of thread which insures durability in this respect and insures a positive drive of the shanks when the sleeve is rotated, while at the same time it simplifies the construction.

Having thus described my invention what I claim as new and desire to secure by Letters Patent is,

40 1. A drill chuck comprising an integral body containing guideways inclined to its axis and open at the surface of the body at the rear portion of the latter, said guideways 45 extending through the forward portion of the body below the surface thereof, threaded jaw members in said guideways, and a sleeve having an integral part thread-engaged with said jaw members, the forward portion of the 50 body being of sufficiently reduced diameter to permit the sleeve to pass over it, when said sleeve is adjusted to engage the threads of the jaws.

55 2. A drill chuck comprising a body containing guideways inclined to its axis and open at the surface of the body at the rear portion of the latter, said guideways extending through the forward portion of the body below the surface thereof, threaded jaw 60 members in said guideways, a sleeve having an integral part thread engaged with said jaw members, the forward portion of the body being of sufficiently reduced diameter to permit the sleeve to pass over it, when said

65 sleeve is adjusted to engage the threads of the jaws, and detachable means for holding said sleeve on said body and constituting the sole medium for retaining the jaw members and sleeve in operative relation with respect to the body.

70 3. A drill chuck comprising a body containing guideways inclined to its axis and open at the surface of the body at the rear portion of the latter, said guideways extending through the forward portion of the body 75 below the surface thereof, threaded jaw members in said guideways, and a one part sleeve thread engaged with said jaw members and having its forward end rotatively bearing on and reinforcing the forward body 80 portion against lateral thrust incurred by the members, the forward portion of the body being of sufficiently reduced diameter to permit the sleeve to pass over it, when said sleeve is adjusted to engage the threads of 85 the jaws.

4. A drill chuck comprising an integral body containing guide-ways inclined to its axis and open at the surface of the body at the rear portion of the latter, said guideways 90 extending through the forward portion of the body below the surface thereof, threaded jaw members in said guide-ways, a sleeve having an integral part thread-engaged with said jaw members, the forward portion of the body being of sufficiently reduced diameter to permit the sleeve to pass over it, when said sleeve is adjusted to engage the threads of the 95 jaws, and a ring located at the rear end of the chuck, adapted to cover the guide-way openings and hold the sleeve to the body portion.

100 5. A drill chuck comprising a body portion having a part with taper sides and the forward part with approximately parallel sides and containing guide-ways at an incline to its axis which are open at the surface of the body at the tapered part thereof and extend through the body below the surface thereof at its forward part, jaw members in 105 said guide-ways, an integral sleeve constructed to operate said jaw members, means for holding said sleeve to said body, the construction being such that by detaching the said holding means, the sleeve and jaws may 110 be freely removed from the body portion.

115 6. A drill chuck consisting of three parts exclusive of the jaw members, comprising a body portion having its rear part tapered and its forward part formed at an angle to said tapered part and containing guideways 120 at an incline to its axis which are open at the surface of the body at its rear tapered part and extend through the body below the surface thereof at its forward part, said forward part being of a diameter not greater than the 125 smallest diameter of its rear tapered part, jaw members in said guideways, an integral sleeve for operating said jaw-members and bearing

against the body portion and extending to the front end of the tapered part, thereby covering the guideway openings, and means for holding said sleeve to the body portion, 5 substantially as described.

In testimony whereof, I, FRANK M. ASHLEY, have signed my name to this specifica-

tion in the presence of two subscribing witnesses, this 7th day of December 1906.

FRANK M. ASHLEY.
